FIG. 4

Des. 197,910

PAGE 5

FIG. 5

FIG. 6

FIG. 1 is a front elevation of a table lighter showing my new design;

FIG. 2 is the back view of the table lighter;
FIG. 3 is the right side view of the table lighter;
FIG. 4 is the left side view of the table lighter;
FIG. 5 is the top plan view of the table lighter;
FIG. 6 is the perspective view of the front of the table lighter.

I claim:

The ornamental design for a table lighter, substantially as shown.
